AWNING

John F. Kramer, Cleveland, Ohio, assignor, by
mesne assignments, to Dracco Corp., Cleveland,
Ohio, a corporation of Ohio

Application August 15, 1947, Serial No. 768,897

4 Claims. (Cl. 20—57.5)

1

This invention relates to louver awnings and more particularly to improvements in the construction, operation, appearance and installability thereof.

It is an object of my invention to provide an awning of improved construction, which can be easily operated both as to louver or vane adjustment and as to bodily adjustment relative to the building to which it is secured. Another object is to provide an awning which is light in weight, weather-tight, compact in construction, economical of manufacture and attractive in appearance. A more specific object is to provide a common axis about which the awning may be swung to vary its inclination with respect to the face of the building or window frame and about which the louver actuating mechanism may be operated and about which a weather seal is maintained. A further object is to provide an awning which is supported in relation to a building in a position providing free access to the outside of the window so that the window can be conveniently washed or otherwise repaired without removing the awning.

Another object is to provide a suspension mounting for such an awning which facilitates attachment to and removal from the building, and which enables bodily movement of the awning about an axis to any desired position, ranging from a vertical position parallel to a window to a fully raised nearly horizontal position. Another object is to provide an awning which is strong and rigid in construction and which will not bend, sag or warp in any position of the awning.

Another object is to provide an awning having side vanes or extensions which serve to exclude the slanting rays of the sun. Still another object is to provide means for adjusting the vanes or louvers of an awning from a point within the interior of the building.

A further object is to provide an improved relation between and disposition of the operating levers and links within the concealment of the side rail elements whereby the appearance as well as the strength and utility of the awning is enhanced. Another object is to provide a sub-assembly of operable vanes or louvers, frame and operating mechanism which as a unit may be readily installed in or removed from its place of use and coaction with other operatively related parts and elements of the awning.

Other objects and advantages will more fully appear from the following description of pre-

ferred forms of my invention reference being had to the accompanying drawings wherein Figure 1 is a perspective view of an awning embodying my invention operatively installed on a building, the louvers of which are shown partially cut away to show the details of the louver mounting and operating mechanism. Figure 2 is a side elevation partly in section of the awning of Figure 1. Figure 3 is a fragmentary sectional view taken along the lines 3—3 of Figure 2 showing the construction of the mounting means. Figure 4 is a sectional view of one of the side frame members of the awning frame, taken along the line 4—4 of Figure 2. Figure 5 is a perspective view of a master louver lever arm. Figure 6 is a perspective view of a standard louver lever arm. Figure 7 is a perspective view of one of the brackets which support the awning relative to the building. Figure 8 is a perspective view of a side or end louver adapted to be secured to my awning. Figure 9 is a perspective view of my awning in closed position with end louvers attached. Figure 10 is a view of the awning of Figure 9 with louvers in open position.

An awning embodying a preferred form of my invention, see Figures 1 and 2, includes movable standard louvers 20 and a master louver 23, a frame 10 comprising side rails 14, a bottom rail 18, a transverse torque shaft 11; the side rails being pivotally mounted to swing about the axis of a torque shaft 11 and the frame and torque shaft being pivotally supported in desirable relation to a window 12 by a pair of installation brackets 13. The frame is pivotally supported from the brackets 13 and hence can be swung bodily to any desired angular position relative to the window 12 and there maintained by a pair of longitudinally adjustable and extensible arms 15 fixedly secured to the bottom rail 18 of the frame at 16 and to the building at 17. The standard louvers 20 and the master louver 23 extend horizontally of said frame and preferably project beyond the side rails 14 of the frame as shown and are pivotally mounted on the side rails of the frame as at 21 and on the torque shaft 11 as at 22 respectively. The louvers are linked together for simultaneous movement thereof by means responsive to rotational movement of the torque shaft 11. Actuating means including link 88 operable from within the building are provided to impart rotational movement to the shaft 11 and thus secure the desired movement of all the louvers. A feature of my invention resides in the piv-

otal suspension of the frame 10 with and through the torque shaft 11 from the brackets 13, see also Figure 3. Preferably this is accomplished with a pair of outwardly extending tubular sleeves or journal members 31 sleeved over the shaft adjacent each side rail and installation bracket, preferably secured respectively to each of the side rails and rotatably supported in appropriate bearings 40 in the installation brackets. The journal members 31 extend through the top ends of said side rails and provide free rotatable support for the torque shaft 11 which is preferably secured against longitudinal movement relative to said sleeves by cotter pins P driven through said shaft at convenient points preferably adjacent the innersides of the side rails 14 and alongside the master louver arms 15, see Figure 3. The side rails have their upper ends terminating in reinforced apertures or ring portions 30 through which journal members 31 extend outwardly. Each journal member preferably takes the form of a hollow sleeve having a cylindrical tubular portion 32 extending through the ring portion of each side rail and having an enlarged flanged end 33 lying adjacent the inner face of the ring portion of the rail. The cylindrical portion 32 of the sleeve 31 projects outward and beyond the aperture 30 and is seated in and pivotally supported by the cylindrical bearing sockets 40 of the installation brackets 13. The shaft is free to rotate within the journal members and also serves as an integral part of the frame. It braces and stiffens the frame, keeps the journal members aligned, and maintains the side rails parallel and true. Preferably the shaft is hexagonal or noncircular in cross-section as will be more fully explained. The frame, including the louvers 20 and 23, the shaft, journals, side rails, louver arms and louver operating mechanism constitutes a conveniently separate sub-assembly suitable for separate shipment and installation with desirable facility.

The installation brackets 13 support the awning in a position somewhat above the window and desirably spaced outwardly therefrom a desirable and substantial distance so that access can be had to the windows for washing or for other purposes without removal of the awning and without unduly limiting the working space. The brackets 13 have vertical leg portions 41 adapted to lie flat against the wall of the building or window frame and to be secured to the wall by lag screws 43 or other suitable means. An inclined portion 42 depends diagonally outwardly and downwardly from the vertical leg portion terminating in a horizontally disposed louver portion 44. As shown in Figures 2 and 7 the inclined portion 42 of the bracket 13 is angled within itself; the upper part thereof 42a inclining downwardly at a gentle slope from the horizontal for a limited distance and providing a seating area upon which the upper and inward part of the canopy 19 is adapted to be secured as by appropriate bolts and nuts or rivets. The leftward and downward portion of the canopy, as viewed in Figure 2, is thus out of contact with the brackets 13 so that its lowermost portion is free to have limited movement for weather sealing purposes and/or installation operations to be more fully explained below. The part of the portion 42 of the bracket 13 leftwardly and downwardly of the part 42a, as viewed in Figure 2, is inclined quite steeply and is spaced from the shaft 11 to afford clearance for the upper and rightward edge of the master louver

23 when the same is rotated about the axis of the shaft as will be more fully explained below. The brackets 13 are stiffened and given added strength, each by means of a longitudinal rib 45 which traverses the under side of the bracket, terminating at maximum depth at the portion 41 and serving to brace the bracket against bending stresses. The lowermost portions 44 of the brackets 13 are provided with laterally extending U-shaped bearing sockets 40 opening upwardly and adapted to receive and support the journal members or sleeves 31 through which the shaft and the frame are pivotally supported for rotation and swinging movements respectively about the shaft axis. A cotter pin C passing through suitable apertures in the upper ends of the U's of the bearing sockets hold the shaft, journal and awning for pivotal movement about the shaft axis and securely against accidental or inadvertent removal.

Another advantage is obtained from the design and construction of the side rails 14 which impart increased rigidity and strength as well as an improved appearance to the awning and frame therefor. Preferably, as best shown in Figure 4, the side rails are formed of light metal such as aluminum strip bent or rolled longitudinally to a U-shaped or, more precisely, a J-shaped section. This section shape is easily and economically produced by roll forming, press-brake or other forming methods, and, beside imparting rigidity to the frame, permits substantial concealment of the louver operating mechanisms. Thus the bottom portions 50 of the side rails are U-shaped providing channels in which the actuating links 60 with the lower ends of the louver arms of the vane operating mechanism are concealed. The outside wall of each rail 14 extends upwardly and is offset inwardly as at 52 so that the extreme upper section 53 of each rail lies in a plane substantially bisecting the lower U-portion of each rail. To stiffen the side rails 14 the top edge of each rail is preferably bent or curled outwardly to form a slight bead or flange 56. In addition it may be found desirable to strengthen and stiffen the upper ends of each side rail adjacent the ring portion 30 by securing thereto a triangularly shaped plate 28 apertured to correspond with that portion of the side rail and secured thereto preferably by riveting or by other suitable means.

The awning frame is symmetrical so that the right hand rail, as viewed in Figure 1, has its wall portion to the outside of the awning while the left rail has its wall portion oppositely disposed and thus also to the outside. Thus the side rails substantially conceal the louver supporting arms and operating mechanisms so that the awning presents an uncluttered, clean and attractive appearance.

The louvers 20 and 23 are mounted on or in respect to each of the side rails so that they can be adjusted from fully closed position in which they lie in overlapping arrangement in a plane parallel to and closely adjacent the side rails to fully open position in which they extend substantially at 90° to the side rails. Any desired number of louvers may be provided depending on the size of the awning. With the exception of the top master louvers 23, the louvers 20 are preferably identical in design, size, shape and in mounting.

Each of the louvers 20 is carried by a pair of supporting arms 70 and riveted to the angled

flanged upper ends 71 thereof by rivets 18 which arms in turn are pivotally connected by pivot pins 21 extending through apertures 74 therein and through the dimpled top edges of the side rails 14. The arms 70 are also pivotally connected by pins 61 at their lower dimpled ends through apertures 73 with the links 60. The louver arms 70 are preferably mutually parallel and are of the same length between the points 21 and 61 whereby to swing equally in unison in response to longitudinal movements of the links 60 under the influence of the torque shaft 11.

A pair of master louver arms 75 support the top or master louver 23 for movement with the louvers 20 but the master arms are fixedly connected in their mid-portions through hexagonal apertures 76 directly to and for rotation with the torque shaft 11 as at 22, Figures 2 and 3. At their lower ends the master arms 75 are apertured at 77 and pivotally connected as at 62 to the upper ends of links 60 thus acting as cranks between the shaft 11 and the actuating links 60. Preferably the axis of the shaft 11 is in line with the axes of the pivot points 21 and the length and direction of the lever arms 75 between the axis of the shaft 11 and their pivotal connections 62 with the links 60 are the same length and parallel with corresponding parts of the levers 70 between the connections 21 and 61 whereby free parallelogram action is afforded among the several arms and links when the shaft is rotated.

Each master arm 75 has a flat angled upper portion 79 secured to and supporting the master louver 23 as by rivets 72. Clockwise rotation of the shaft 11 as viewed in Figure 2 gives clockwise rotation to the louver 23 and the master lever arms 75 which latter movement is transmitted to the actuating links 60 and causes downward, as viewed in Figure 2, movement of the links within the channels of the side rails 14 and thereby turns each of the lever arms 70 in a clockwise direction moving all the louvers equally toward open position. Conversely counter-clockwise motion of the shaft will tend to close all the louvers.

I prefer that the arms 70 and 75 support the louvers so that in closed position they will lie in weatherproof, overlapping relationship close or proximate to the top edges of the side rails. Geometry necessitates that if the louvers 20 lie quite close to the rails they either be attached to the parts 71 of the arms 70 far enough leftwardly and downwardly, as viewed in Figure 2, of their pivot points 21 to admit their turning to right angles with the rails before their upper edges contact the rails, or that the top edges of the rails be notched somewhat as at 55 to accommodate the upper edges of the louvers when the said upper edges lie both close to and upwardly, as viewed, of their pivot points. Alternatively when the louvers are carried more remotely from their pivot points and from the top edges of the rails their upper edges may lie more rightwardly and upwardly, as viewed in Figure 2, without contacting the top edge of the side rails when turned at right angles thereto. Within the precepts of my invention wide choice is facilitated for mounting the louvers relative to their pivot points with or without notching the top edges of the rails as costs, balance and other considerations of design suggest. I prefer that louvers 20 be supported by the arms 70 substantially as shown in Figure 2 with about three quarters of the louver leftwardly of the pivot point whereby gravity tends to close the louvers. With the louvers lying close to the side rails I am able to use shorter arms and

therefore notch the rails as at 55 substantially as shown. If desired, the louvers can be supported at their extreme rear edges, or spaced farther away from the rails, so that the notches can be dispensed with entirely. To counteract the action of gravity partially, though desirably not entirely, it is practicable to provide a pair of coil springs S disposed respectively within the side rails 14, and secured to the side rails adjacent their lower ends as at 111 and to the actuating links 60 as indicated at 112. The springs may be stressed as desired to counteract the unbalanced weight of the louvers and linkage wherewith to give such ease of operation as may be desired, preferably without removing all the tendency of the louvers to remain shut in the closed position.

The master louver 23 in addition to acting with the louvers 20 as hereinabove described participates in a weather-sealing function with the canopy 19, Figures 1 and 2, and is formed and situated to do its work throughout a wide range of angular relations between the awning frame and the window or building as well as in its several angular relations to the side rails of the frame. 20 The canopy 19 may have the same length as the louvers 20 and 23 and is preferably made of yielding sheet stock, such as rolled aluminum, and fixedly secured adjacent its upper and rightward edge as viewed in Figure 2, to the inclined portions 42a of the installation brackets 13 and preferably in sealed or flashed relation with the wall of the building or window frame. The width of the canopy, i. e. the dimension seen in Figure 2, is such as to extend the canopy, at the desired 25 inclination from the wall or building surface, to approximately the vertical plane of the shaft 11. The lower and leftward portion of the canopy 19 preferably terminates in a vertically depending lip 29 lying substantially in or with its lower edge 30 35 inclined from the wall or building surface, to approximately the vertical plane of the shaft 11. The lower and leftward portion of the canopy 19 preferably terminates in a vertically depending lip 29 lying substantially in or with its lower edge 40 45 50 55 60 65 70 75 80 85 90 95 100 105 110 115 be disposed more nearly the vertical when the louvers are closed the flange 39 may bear on the lower part of the lip 29 and yieldingly move the lip 29 a little away from its vertical position; the length and yieldability of the lip 29 accommodating the movement of the flange 39 to this extent. Similarly if the awning be positioned so nearly horizontal that the flat leftward, as viewed, part of the louver 23 should contact the lip 29 when the louver is opened, the lip can yield to accommodate this contact and movement. As viewed in Figure 2 the rightward edge of the curved portion 24 of the louver 23 might in an extreme clockwise turning movement contact the part 44 of the brackets 13 adjacent the bearing 40 and undesirably limit movement of the louver under some circumstances. As presently advised I prefer to notch the edge of the louver adjacent the bracket to admit the desired turning movement or alternatively I find it practicable to form the part 44 of the brackets concave upwardly adjacent the bearing 40 wherewith to admit the maximum desired turning of the louver 23 where the inclination of the awning would otherwise cause the contact and conflict mentioned.

To install my awning it is preferable that the brackets 13 first be secured to the building or window frame with the bearings 40 open to receive the shaft 11 and/or shaft and sleeves 31 and, if desirable, with the canopy 19 secured to the brackets as above described. Thereupon the awning frame with all of the louvers operatively assembled therewith and with the shaft 11 may be inserted from a position a little leftwardly and below that shown in Figure 2 to the position shown in Figure 2, the shaft 11 and sleeves 31 being moved upwardly from the front of the open bearings 40 and then inwardly and downwardly thereinto whilst the arcuate portion 24 of the louver 23 engages the lower edge of the lip 29 and raises the free resilient forward portion of the canopy 19 wherewith to admit the parts to their operative and assembled relation. The lower edge of the lip 29 preferably retains substantial contact with the arcuate part 24 as the shaft is lowered down into the bearings 40, and thereafter the insertion of the cotter pins C completes the assembly as above mentioned. Alternatively the installation above described may and oftentimes is advantageously done before the canopy 19 is attached to the brackets 13. Under these circumstances the placing of the shaft and/or journal members in the bearings 40 is much facilitated and is often to be preferred except perhaps in installations where the latter attachment of the canopy 19 to the brackets is awkward by virtue of the height or location of the window adjacent to which the awning is mounted. After either manner of mounting frame and canopy it remains only to attach appropriate means to rotate the shaft on the one hand and to position and secure the frame angularly with respect to the window or building on the other hand to complete the installation.

To effect rotational movement of the shaft 11, I prefer to provide a vertical rod or link 80 pivotally secured to a crank lever 81, Figures 2 and 3, which is non-rotatably secured to the shaft. The lower end of the rod 80 is in turn pivotally secured to a lever 82 which extends from the wall of the building and which may be given vertical rocking motion by manually operated means 83 from within the building, the details of which need not be described but which may comprise a worm and worm wheel or other arrangement suit-

able to convert rotation of the handle 83 in vertical swinging movement of the lever 82. Up and down vertical movement of the rod 80 is transmitted by the lever 81 to produce rotation of the torque shaft 11. Preferably the lever 81 has a hexagonal aperture 84 having a snug sliding non-rotatable fit with the shaft 11 for quick non-rotatable attachment therewith. By cotter pins, not shown, or by peening the shaft to the lever the lever is conveniently secured against undesirable longitudinal movement along the shaft. Preferably the awning will be swung to its desired inclination about the shaft axis with reference to the window before the lever 81 is slipped onto the shaft 11 whereby a desirable relation between the lever and shaft may be selected with respect to the angular position the shaft will assume in accordance with the inclination of the awning. Preferably, as shown in Figure 3, the lever 81 is merely slipped over one of the exposed ends of the shaft 11 with much convenience. I do not exclude however the practice of securing the lever to the shaft at any other position that may be more desirable under certain circumstances either from the point of view of torsional deflection of the shaft or from accessibility to or alignment with the operating means 83 or otherwise as convenience or expediency may suggest. Neither do I limit my invention to any specific means of making a non-rotatable connection between the lever and the shaft.

Referring again to Figure 3, my teaching is not necessarily limited to the employment of the shaft 11 in hexagonal form nor to the use of the sleeves 31 in conjunction therewith. For example I have found it desirable to employ the shaft 11 in a smoothly cylindrical exterior form, journaling the shaft directly in the bearings 40 and pivoting the ends of the side rails directly to the shaft without the interposition of any sleeves or bushings therebetween. The smooth cylindrical form of shaft requires specifically different means for engagement of the lever arms 75 and the lever crank 81 therewith as distinguished from the convenient non-circular mating of the holes 76 and 84 therewith. I prefer to provide integral cylindrical drawn flanges F on the lever arms and crank as illustrated in dotted lines as to the crank 81 (a corresponding flange for the arm 75 not being shown for the sake of clarity in the drawing) and then drill and pin the arms and crank to the shaft in situ as by taper pins T to secure them to the shaft in the desired angular positions. The smooth external shaft in this form of my invention performs substantially the same offices and functions as the non-circular shaft and acts directly as the pivotal axis of the awning and as the top frame member and rotating axis for the louvers and otherwise as above described.

In order to hold the awning in the desired angular position relative to the window, adjustable extensible support arms 15 are secured to the bottom rail 18 near each end of the awning. Preferably the arms 15 are made of tubular elements 120 and 121, whose flattened and bent ends 123 and 125 respectively are secured to the wall or window frame by screws or bolts as at 17 and to the bottom rail 18 as at 16 by rail embracing reentrant bend as shown. The effective length of each support arm may be selected and adjusted preferably by inserting a smaller rod or tube 125 of approximately the desired length telescopically within the juxtaposed open ends of each of the tubes 120 and 121 and if desired, holding the

parts in the desired fixed relation thereto by drilling and pinning the tubes 120 and 121 and the rod 125 together in situ.

If desired my awning may be provided with side louvers or extensions, Figures 8, 9 and 10, which serve to exclude those slanting rays of the sun which may reach the window around the end of the awning. Such a side louver 109 is shown in Figure 8 and comprises an angled flange 101 which may be permanently or removably secured to the end of a main louver 20 or 23 by rivets or bolts 102, wherewith to dispose the main body or panel 103 thereof to lie and swing in a plane substantially normal to the axis about which the louver pivots. Side louvers 100a-d, differing only from the side louver 109 only in length, may be secured to as many of the louvers 20 as may be desired. It may be necessary or desirable to provide only the uppermost louvers with side extension louvers but I have illustrated a small awning in which all the louvers are so provided; the several side louvers being respectively of different lengths whereby their free, rightward as viewed, ends will line up in closed position desirably close to the window frame or building wall to create the desired protection against the slanting rays. An angled extension member 104 may be similarly secured to the end of the canopy 19 to overlap the louver 100 and complete the enclosure. When the main louvers 20 and 23 are in fully closed position the side louvers also preferably take a fully closed partially overlapping position, each side louver overlapping slightly the side louver adjacently below it as shown in Figure 9. When the main louvers 20 and 23 are in fully open position or nearly fully open position, the side louvers take the position shown in Figure 10, there being sufficient clearance provided so that the side louvers may fan together without locking or clashing.

While I have illustrated and described a preferred and certain modified forms of my invention I am aware that changes, modifications and improvements therein will occur to those skilled in the art without departing from the essential characteristics thereof or from the substance of my teaching herein, and I do not care to be limited in the scope and effect of my patent to the specific forms herein described in exemplification of my invention nor in any manner other than by the claims hereof fairly construed.

I claim:

1. A louver awning comprising side rails, louvers pivotally supported on said side rails, an operating shaft, said side rails being pivotally supported for swinging movement about the axis of said operating shaft, means for rotating said operating shaft, means for transmitting shaft movement to said louvers, means for swinging said side rails about the axis of said shaft, means for supporting said shaft on a fixed axis while the shaft is rotated and while said side rails are swung including bearing means adapted to be secured to the building upon which the awning is mounted and pivotally supporting said awning about said axis, a weather seal element extending from said building above and spaced from said axis, and a louver element rotatably mounted to swing about said axis and interposed between said axis and said weather sealing element, said elements having yielding and sliding contact, one of said elements having an arcuate portion in

contact with the other struck from said axis as a center.

2. A louver awning comprising movable louvers, a louver operating shaft rotatably mounted on an axis adapted to be supported in fixed relation to the building surface with which the awning is associated, louver-supporting side rails extending transversely of said shaft and pivotally supported for swinging movement about the axis of said shaft, the uppermost louver of said movable louvers having pivotal movement about said shaft axis and having a cylindrical portion struck from said axis, a weather sealing member contacting said portion of said louver, an operating lever for rotating said shaft engageable therewith, means for supporting said shaft for rotation about its own axis, means for positioning said side rails about the same axis and means actuated by said shaft for moving said louvers.

3. A louver awning comprising movable louvers, a louver operating shaft rotatably mounted on an axis adapted to be supported in fixed relation to the building surface with which the awning is associated, louver-supporting side rails extending transversely of said shaft and pivotally supported for swinging movement about the axis of said shaft, an operating lever for rotating said shaft engageable therewith, means for supporting said shaft for rotation about its own axis including supporting brackets having upwardly facing openable bearings in which said shaft is removably journaled, bushings in which said shaft is journaled being secured to and extending through said side rails, said bushings comprising direct pivotal supports for said frame and being removably supported in said bearings, means for positioning said side rails about the same axis and means actuated by said shaft for moving said louvers.

4. A louver awning comprising a frame including side rails and a top louver member mounted on said side rails, brackets pivotally supporting said frame for movement about a fixed axis, a weather seal member mounted on said brackets, one of said members having a cylindrical surface and the other of said members having an edge having wiping engagement with said cylindrical surface, the axis of said cylindrical surface being substantially coincident with said fixed axis whereby the engagement of said members is maintained for every pivotal position of said louver member.

JOHN F. KRAMER.
